UNITED STATES PATENT OFFICE.

PAUL B. NAYLOR, OF KANSAS CITY, MISSOURI.

SILO.

1,019,180.

Specification of Letters Patent.

Patented Mar. 5, 1912.

Application filed June 12, 1911. Serial No. 632,629.

To all whom it may concern:

Be it known that I, PAUL B. NAYLOR, a citizen of the United States, residing at Kansas City, in the county of Jackson and 5 State of Missouri, have invented certain new and useful Improvements in Silos; and I do declare the following to be a full, clear, and exact description of the invention, such as will enable others skilled in the art to which 10 it appertains to make and use the same.

This invention relates to improvements in silos.

The object of the invention is to provide a silo having an improved foundation and 15 means for forming an air and water tight connection between the lower ends of the sides or wooden staves of the silo and the foundation which will permit the expansion and contraction of the silo.

20 With this end in view, the invention consists in the details of construction herein-after more fully described and claimed.

In the accompanying drawings; Figure 1 is a vertical sectional view through a silo 25 constructed in accordance with my invention; Fig. 2 is a cross sectional view on a large scale through one side of the foundation and the adjacent part of the side of the silo; Fig. 3 is a plan view of a portion of 30 the foundation of the silo showing the channel therein for receiving the lower ends of the staves forming the sides of the silo.

Referring more particularly to the drawing, 1 denotes the body portion or sides of 35 the silo, here shown as constructed of vertically disposed staves which are secured together near their upper and lower ends by pairs of annular binding rods or hoops 2 and 3 on opposite sides of the staves as 40 shown. The rods are held in position near the ends of the staves by a series of staples or U-bolts 4 which are inserted through the staves and have their inner ends engaged with clip plates 5, said ends having screwed 45 thereon clamping nuts 6. The staves forming the sides of the silo are further secured together by upper and lower flat metal bands or hoops 7.

The silo is supported upon an annular 50 foundation 8 formed of concrete or other suitable material the lower portion of which is set into the ground to a suitable depth as shown. In the upper side of the foundation

8 is formed an annular groove or channel 9 into which are seated the lower ends of the 55 staves forming the sides of the silo, said lower ends of the staves being arranged in the center of the groove or channel as shown. The channel is of considerably greater width than the thickness of the 60 staves thus providing a space on the opposite sides of the latter to receive a sealing or wood preserving compound 10 which preferably consists of coal tar or the like. When the sealing composition has been placed in 65 the groove or channel on both sides of the staves an air and fluid tight seal is formed between the ends of the staves and the foundation and said lower ends of the staves are effectually prevented from rotting. The 70 filling of coal tar or the like between the staves and the opposite sides of the wide channel 9 will permit the expansion and contraction of the staves forming the sides of the silo.

75

The silo is preferably braced near its upper end by a series of inclined brace rods 11 the upper ends of which have a loose connection with the U-bolts 4 of the upper pair of hoops 2 while their lower ends have a 80 loose connection with stakes 12 driven into the ground adjacent to the outer side of the foundation as shown. By thus loosely connecting the ends of the braces 11 the latter will not interfere with the expansion or 85 contraction of the sides of the silo or with the adjusting of the same.

From the foregoing description taken in connection with the accompanying drawings, the construction and operation of the invention 90 will be readily understood without requiring a more extended explanation.

Various changes in the form, proportion and the minor details of construction may be resorted to without departing from the 95 principle or sacrificing any of the advantages of the invention as defined in the appended claim.

Having thus described my invention, what I claim is:

100

The herein described silo comprising a cylindrical body consisting of upright wooden staves and means for holding them together, a foundation of concrete formed in the shape of a ring rising partly above the 105 surface to the ground and having in its up-

per edge an annular groove wider than the thickness of said staves, the lower end of the body resting in the body of said groove between its side walls, and a sealing compound 5 in the groove between both sides of the staves and the walls of the groove.

In testimony whereof I have hereunto set

my hand in presence of two subscribing witnesses.

PAUL B. NAYLOR.

Witnesses:

E. W. CURTIS,
RAY L. BAILEY.
